DESIGN FOR A SIGNAL COVER GLASS

Charles Adler, Jr., Baltimore, Md.

Application January 14, 1938, Serial No. 74,307

Term of patent 14 years

To all whom it may concern:

Be it known that I, Charles Adler, Jr., a citizen of the United States, residing at Baltimore, State of Maryland, have invented a new, original, and ornamental Design for a Signal Cover Glass, of which the following is a specification, reference being had to the accompanying drawing, forming a part thereof.

Figure 1 is a rear elevational view of a signal cover glass, showing my new design.

Figure 2 is a section on the line 2--2 of Figure 1, and

Figure 3 is a section on the line 3--3 of Figure 1.

I claim:

The ornamental design for a signal cover glass as shown.

CHARLES ADLER, JR.
